COLLAPSIBLE FORM.

1,327,333.

Specification of Letters Patent.

Patented Jan. 6, 1920.

Application filed December 6, 1918. Serial No. 265,622.

To all whom it may concern:

Be it known that we, LORENZO O. LAMKIN and JOHN H. BERGHAUS, Jr., citizens of the United States, residing in the city of Louis-

ville, county of Jefferson, and State of Kentucky, have invented a new and useful Collapsible Form, of which the following is a specification.

This invention relates to collapsible forms 10 of a character adapted for use in the art of paper box making, and more particularly adapted to be used in connection with an ending machine, although it may be found serviceable in other connections.

15 In a certain style of paper box, the bottom and sides thereof are formed from one sheet, the ends being affixed to flanges which are turned inward from the ends and sides. In order to insure adhesion and hasten the setting of the adhesive, great pressure is applied to the flanges and superimposed end pieces. The method being, for the operator to place a blank, the parts of which are delimited by score lines, against the end of a

20 form, the width of which is the same as that of the interior of the box to be formed and the length thereof equal to, or greater than that of the depth of the box to be formed. With the palm of the hand, the sides are

25 bent back on the scored lines, to lie against the sides of the form and the flanges are bent down, with the thumbs and fore fingers, to lie on top of the form. The box end is then positioned on the flanges. The form

30 is carried on a moving part of a press, which when released by means of a foot lever carries the form against a head, whereby great pressure is exerted upon the end and flanges in place on the form. If the operator does 35 not exercise due precaution, his thumb or fingers will be caught and crushed between the advancing form and the head of the press.

An object of this invention is to provide a 40 form adapted to be used for the purpose set forth above, the walls of which will yield or collapse, if the operator's fingers or thumb, or any other obstruction should be interposed between the top of the form and 45 the head of the press.

With the foregoing and other objects in view, the invention consists of the novel construction and arrangement of parts illustrated in the accompanying drawing, which 50 forms a part of this specification, wherein is set forth an embodiment of the invention,

but it is to be understood that such changes and modifications may be resorted to as come within the scope of the appended claims.

60 In the drawings, comprising two sheets, wherein similar reference characters designate like parts in the several views, Figure 1, is a perspective view of an embodiment of the invention: Fig. 2, an elevation of the rear end thereof, the fixed head and the movable bed of the press being indicated by dotted lines: Fig. 3, a top plan view, some parts being removed, some broken away and others in section, the better to 65 show the construction, one locking element being shown in a normal position and the other in operated position: Fig. 4, a section on line 4—4 of Fig. 3: Fig. 5, a section on line 5—5 of Fig. 3: Fig. 6, a perspective 70 view of one of the locking tumblers showing the underside thereof: Fig. 7, a perspective view of an end wall showing the inner face thereof and Fig. 8, a plan view of a blank 75 of the style referred to.

80 The embodiment of the invention illustrated herewith comprises a rectangular base —10— on the under side of which is a longitudinal rib —11— which assists in positioning the form on the bed —8— of a press 85 in connection with which it is to be used. On the upper side of the base is a centrally positioned longitudinal rib —12— which extends a spaced distance forward from the rear end thereof and a block —13— positioned a spaced distance from the forward end of the base and in alinement with the rib 12.

90 A pair of skeleton frames are disposed on either side respectively of the central rib and are adapted to be shifted transversely on the base. These frames are identical except that one is right hand and one is left hand. Each comprises a stringer —15— which lies parallel with the rib and extends from the rear end of the base to 95 within a spaced distance of the forward end thereof. A right and left handed screw —16— arranged transversely of the base is engaged in projections —17— which depend from the stringers 15, and move in a groove 100 —18— in the base. It is clear that turning the screw will advance and withdraw the frames and their associated elements from and to the center of the base, thus adapting the frame for use in making boxes of different sizes. The frames are guided in their movement to and fro by ribs —19— posi-

105 110

tioned on the base. An angular extension, or arm —20— at the rear end of the stringer parallels the end of the base and a post —22— is erected vertically on the free end 5 of this arm. Normally the post stands over the rear corner of the base. From the forward end of the stringer a curved arm —23— extends outward and forward and supports a post —24— over the forward 10 corner of the base. The posts 22 and 24 are provided on their opposed sides with grooves —26— in which are disposed sliding blocks —27— which are upheld by means of springs —28—. The rear posts 22, extend the full 15 height of the frame but the forward posts terminate a spaced distance therefrom, being only of such height as is necessary to accommodate the blocks 27. A side wall, or wing —30— is pivotally mounted in the 20 blocks 27 by means of gudgeons —31—. The upper edge of this wall is normally flush with the top of the rear post and the lower edge is a spaced distance above the base. The springs 28 permit the wall to be 25 depressed, and their tension is such that if a finger is caught between the top of the wall and the head of the press, they will yield without hurting the finger. The lower forward corner of the wall is cut away to 30 adapt it to fit over the curved arm 23, when the wall is depressed. A plate —33— secured to the forward side of the front post 24, by screws —34— extends a spaced distance therefrom and is provided on its inner edge with an inturned flange —35— which parallels the post. An end wall 35— has a tongue —37— on its outer edge, which is slidably received in a vertical groove —38— in the front post 24, and is provided on its face with a groove —39— for the reception of the flange 35, on the plate. By this construction the end wall is rigidly associated with the post and is freely movable relative thereto 40 in a vertical plane. A spring pressed plunger —40— disposed in a vertical bore —41— extends downward therefrom with its lower end resting on the base, and serves to yieldingly maintain the wall in its normal 45 position, that is with its upper edge flush with that of the side walls. An arm —43— extended from the end wall overhangs the front post 24 and is spaced thereabove, the distance through which the end wall may be depressed. A recess, or notch —44— on the inner side of this arm near the outer end thereof, is adapted to receive a pin, or projection —45— on the forward end of the side wall, 30, whereby normally 50 the side wall is retained in a vertical position, also if the end wall is depressed it will carry the side wall with it. A slight depression of the side wall will free the pin, 45, from the notch 44, when the top of the 55 wall will naturally, under the pressure of

the operator's hand, swing inward, there being a recess —46— on the inner face of the end wall which provides a path for the pin. It will be observed that the side walls may be depressed bodily against the tension 70 of the springs 28, that they may be turned on the horizontal pivots 31, when the pins 45 are clear of the notches 44, and that there is sufficient clearance between the ends of the side walls and the respective posts to 75 permit of their depression, without danger of binding by pressure on either end thereof, so that depression of an end wall will depress the adjacent end of its associated side wall. The tension of the springs, which 80 uphold the walls, is such that they will not yield under the weight of the operator's hand nor by reason of the necessary manipulation attending the placing of a blank, but if a digit is caught between the upper edge 85 of the form and the head —9— of the press they will yield without exerting pressure sufficient to injure the trapped member. The pressure normally exerted by an operator's fingers in positioning a blank is directed inward against the upper edges of the walls and in event the pin 45, is released from the notch 44, tends to swing the wall inward as described. The mechanism will 90 now be described, by means of which the 95 walls are locked in position and adapted to sustain the pressure necessary to attach the end of the box. Upon the upper side of the stringer of each of the skeleton frames, a bar —50— is slidably mounted, being retained by means of screws —51— which pass through slots —52— into the stringer. The bar 50 extends from a point a spaced distance from the forward end of the stringer to a spaced distance beyond the rear end 100 thereof and is provided with a slot —53— in the extended portion. A bracket —54— secured to the arm 20, depends therefrom to the lower edge of the base. A shaft —55— mounted in bearings —56—, carried by the 110 bracket is provided on its inner end with a vertical arm —57— which is engaged in the slot 53, in the sliding bar 50, and on its outer end with an arm —58— which is operatively connected with a vertical rod —59— 115 which is slidably mounted in brackets —60— which are attached to the post 22. The rod extends above the post a spaced distance less than the thickness of the digits of an operator's hand, the arrangement being such that as the form approaches the head of the press, the rods 59 will be depressed and the sliding bar thereby drawn backward. A locking bolt —61— located on the base forward of the curved arm 23, in substantial 120 alignment with the stringer, and guided by a rib —62— is adapted to be pushed forward under the edge of the front wall. A link —63— operatively connects the block with a lever —64— which is fulcrumed on the 125 130

stringer at —65—. The other end of the lever 64 is connected with the sliding bar by means of a coil spring —66—, the tension of which is such that normally retraction 5 of the bar will advance the bolt under the end wall and prevent depression thereof, but should the wall have been depressed before the bar is actuated and forward movement of the bolt be prevented by contact therewith, the spring 66, will yield and permit the movement of the bar to proceed without detriment to the structure. The sliding bar and associated elements are returned to normal position by means of a 10 spring —67—. A rod —68— inclosed within the coiled spring 66, enables the sliding bar to exert a direct push on the lever 64 to return the bolt to normal position. A locking tumbler —70—, positioned on the 15 base longitudinally, and movable transversely thereon, is provided on its lower surface with a groove —72— which fits over the screw 16, and with grooves —73— which seat on the ribs 19, by which it is 20 guided in its movement, a projecting portion —75— overhanging the stringer. A plurality of triangular projections —76— extended from the outer edge of the sliding bar, have upturned flanges —77— on their 25 longer sides, which are disposed at a suitable angle to the bar. These flanges are received in corresponding grooves —78— in the under surface of the overhang 75. The arrangement being such that as the bar 30 is drawn back, the tumbler will, by action of the flanges, 77, in the grooves 78, be forced outward under the side wall and will effectively prevent any movement thereof either vertical or rotary. Should a digit, as 35 it is being withdrawn, be caught between an approaching pressure element and the upper edge of a side wall, 30, the wall will be partially depressed, its lower edge moving into the outward path of a tumbler 70, 40 which as it is moved outward will push thereagainst, thereby swinging the wall on its pivots and releasing the digit. Return of the bar, under stress of the spring 67, withdraws the tumbler from under the wall. 45 Movement of the end walls being blocked by the locking bolts 61, and of the side walls by the tumblers 70, pressure may now be exerted upon them the same as if they were 50 normally rigid. A floor —80— which is placed over the mechanism rests upon the rib 12, and block 13, to which it is secured. 55 It is thought that the foregoing description will enable anyone skilled in the art pertaining thereto to make and use the same. 60 Having thus described our invention we claim:

1. In combination with pressure applying elements, a form as characterized, comprising a base, side and end walls suitably supported thereon and adapted to yield under

pressure, means positioned on said base and engageable with said walls to prevent them from yielding, said means adapted to be actuated by said pressure element upon its approximation to the walls. 70

2. In combination with pressure applying elements, a form as characterized, comprising a base, a wall yieldingly supported thereon, a locking element on said base adapted to be engaged with said wall to prevent yielding thereof said element adapted to be actuated by an approaching pressure applying element. 75

3. In a form as characterized, a base, walls yieldingly supported thereon, locking elements adapted to be engaged with said walls to prevent movement thereof, actuating means operatively connected with said elements and extending a spaced distance above the walls. 80

4. In a form as characterized, a base, parallel side walls and an end wall suitably supported thereon and adapted to be depressed perpendicularly relative thereto, locking elements disposed on said base and adapted to be projected under said walls to prevent depression thereof. 90

5. In a form as characterized, a base, posts erected on said base, walls yieldingly supported between said posts and locking elements positioned on the base and adapted to be engaged with said walls to prevent yielding thereof. 95

6. A form comprising a base, posts erected thereon, walls positioned between said posts and movable vertically relative thereto, the lower edge of said walls being a spaced distance above said base, resilient means opposing the downward movement of the walls, locking elements disposed on the base and adapted to be projected under the walls to prevent downward movement thereof, actuating means operatively connected with said locking elements and operating means connected with said actuating means and extending a spaced distance above the posts. 100

7. A form as characterized, comprising a base, posts erected thereon, side walls pivotally mounted between said posts and adapted for vertical and rotary movement relative thereto, said walls terminating a spaced distance above the base, resilient means opposing downward movement thereof, locking elements disposed on the base and adapted to be projected under the walls to prevent downward movement thereof, actuating means operatively connected with said locking elements and operating means connected with said actuating means and extending a spaced distance above the posts. 115

8. A form as characterized comprising a base, posts erected on the corners thereof, the front and rear posts respectively having vertical slots in their opposed sides, blocks slidably disposed in said slots, springs 130

adapted to hold said blocks at the upper end of the slots, side walls pivotally mounted in the blocks, locking elements disposed on the base and adapted to be projected under the walls to prevent downward movement thereof, actuating means operatively connected with said locking elements and operating means connected with said actuating means and extending a spaced distance above the posts.

9. A form as characterized comprising a base, posts erected on the corners thereof, the front and rear posts respectively having vertical slots in their opposed sides, blocks slidably disposed in said slots, springs adapted to hold said blocks at the upper end of the slots, side walls pivotally mounted in the blocks, an end wall slidably associated with a front post, resilient means adapted to hold said end wall at its upper limit of movement, interengaging means between the end wall and the adjacent side wall whereby depression of the end wall will cause a corresponding depression of the side wall but which will permit independent depression of the side wall, locking elements disposed on the base and adapted to be projected under the walls to prevent downward movement thereof, actuating means operatively connected with said locking elements and operating means connected with said actuating means and extending a spaced distance above the posts.

10. A form as characterized a base, posts erected on the corners thereof, the front and rear posts respectively having vertical slots in their opposed sides, blocks slidably disposed in said slots, springs adapted to hold said blocks at the upper end of the slots, side walls pivotally mounted in the blocks, an end wall slidably associated with a front post, resilient means adapted to hold said end wall at its upper limit of movement, interengagable means between the end walls and the adjacent side wall which prevents rotary movement of the side wall without first depressing it slightly to free it from engagement with the end wall but whereby primary depression of the end will carry the side wall with it.

11. A form as characterized comprising a base, posts erected on the corners thereof, the front and rear posts respectively having vertical slots in their opposed sides, blocks slidably disposed in said slots, springs adapted to hold said blocks at the upper end of the slots, side walls pivotally mounted in the blocks, an end wall slidably associated with a front post, resilient means adapted to hold said end wall at its upper limit of movement, interengageable means between the end walls and the adjacent side wall which prevents rotary movement of the side wall without first depressing it slightly to free it from engagement with the end wall

but whereby primary depression of the end will carry the side wall with it, locking elements disposed on the base and adapted to be projected under the walls to prevent downward movement thereof, and actuating means operating with said locking means and operating means connected with said actuating means and extending a spaced distance above the posts.

12. A form as characterized, comprising a base, posts erected thereon, walls positioned between said posts and movable vertically relative thereto, the lower edge of said walls being a spaced distance above the base, resilient means adapted to hold the walls at the upper limit of their movement, a bar slidably positioned longitudinally on the base, a rod slidably mounted on the rear post and extended a spaced distance thereabove, operative connections between said rod and said bar whereby depression of the rod will move the bar, resilient means adapted to return the bar and rod to normal position, locking elements adapted to be engaged with the walls to prevent depression thereof, and operative connections between said elements and the sliding bar.

13. A form as characterized comprising a base, posts erected on the corners thereof, the front and rear posts respectively having vertical slots in their opposed sides, blocks slidably disposed in said slots, springs adapted to hold said blocks at the upper end of the slots, side walls pivotally mounted in the blocks, a bar slidably positioned longitudinally on the base, a rod slidably mounted on a rear post and extended a spaced distance thereabove, operative connections between said rod and said bar, whereby depression of the rod will move the bar, resilient means adapted to return the bar and rod to normal position, locking elements adapted to be engaged with the walls to prevent depression thereof, and operative connections between said elements and the sliding bar.

14. A form as characterized comprising a base, posts erected on the corners thereof, the front and rear posts respectively having vertical slots in their opposed sides, blocks slidably disposed in said slots, springs adapted to hold said blocks at the upper end of the slots, side walls pivotally mounted in the blocks, an end wall slidably associated with a front post, resilient means adapted to hold said end wall at its upper limit of movement, interengaging means between the end wall and the adjacent side wall whereby depression of the end wall will cause a corresponding depression of the side wall but which will permit independent depression of the side wall, a bar slidably positioned on the base, a rod slidably mounted on a rear post and extended a spaced distance thereabove, operative con-

nections between said rod and said bar, whereby depression of the rod will move the bar, resilient means adapted to return the bar and rod to normal position, locking elements adapted to be engaged with the walls to prevent depression thereof and operative connections between said elements and the sliding bar.

15. A form as characterized, comprising a base, posts erected on the corners thereof, the front and rear posts respectively having vertical slots in their opposed sides, blocks slidably disposed in said slots, springs adapted to hold said blocks at the upper end 10 of the slots, side walls pivotally mounted in the blocks, an end wall slidably associated with a front post, resilient means adapted to hold said end wall at its upper limit of movement, interengaging means between the 20 end wall and the adjacent side wall which prevents rotary movement of the side wall without first depressing it slightly to free it from engagement with the end wall but whereby primary depression of the end wall will carry the side wall with it, a bar slidably positioned longitudinally on the base, a rod slidably mounted on a rear post and extended a spaced distance thereabove, operative connections between said rod and said 25 bar whereby depression of the rod will move the bar, resilient means adapted to return the bar and rod to normal position, locking elements adapted to be engaged with the walls to prevent depression thereof, and operative 30 connections between said elements and the sliding bar.

16. A form as described, comprising a base, posts erected on the rear corners thereof, other posts of less height erected on the 40 front corners, the front and rear posts on the respective sides having vertical slots in their opposed sides, spring supported blocks slidably mounted in said slots, side walls pivotally mounted in said blocks, the front posts having vertical grooves in their opposed sides, an end wall slidably mounted in said grooves, resilient means adapted normally to hold said end wall at the upper limit of its movement, interengaging means 45 between the end and side walls whereby a side wall may be depressed independent of the end wall, but depression of the end wall will carry the side wall with it and means adapted to lock the walls in their elevated 50 position.

17. A form as described, comprising a base, posts erected on the rear corners thereof, other posts of less height erected on the front corners, the front and rear posts on the respective sides having vertical slots in their opposed sides, spring supported blocks 60 slidably mounted in said slots, side walls pivotally mounted in said blocks, the front posts having vertical grooves in their opposed sides, an end wall slidably mounted in

said grooves, resilient means adapted normally to hold said end wall at the upper limit of its movement, interengaging means between the end and side walls whereby a side wall may be depressed independent of 70 the end wall but depression of the end wall will carry the side wall with it, a bar slidably positioned on the base, a rod slidably mounted on the rear post and extended a spaced distance thereabove, operative connections between said rod and said bar whereby depression of the rod will move the bar, resilient means adapted to return the bar and rod to normal position, locking elements adapted to be engaged with the walls to prevent depression thereof and operative connections between said elements and the sliding bar.

18. In a device as characterized, a base, a pair of independent elements positioned 85 thereon, and adapted to be shifted transversely thereof, each of said elements comprising a stringer, an arm extended from each end thereof, a post erected on the end of the rear arm, a shorter post erected on 90 the end of the front arm, said posts having vertical slots in their opposed sides, spring supported blocks slidably positioned in said slots, a side wall pivotally mounted in said blocks, an end wall slidably associated with 95 the front post, resilient means adapted to hold said end wall at the upper limit of its movement, interengaging means between said end wall and the end of the adjacent side wall whereby depression of the end wall 100 will depress the side wall but which will allow the side wall to be depressed independently, a bar slidably positioned longitudinally on the stringer, a rod slidably mounted vertically on the rear post and extended 105 a spaced distance thereabove, operative connections between said bar and rod whereby depression of the rod will draw the bar backward, a spring adapted to return the bar, locking elements adapted to be moved 110 under the walls to prevent depression thereof and operative connections between said elements and the bar.

19. In a device as characterized, a base, a work supporting member erected thereon 115 and resiliently supported a spaced distance thereabove and an element movable to a position under said member to rigidly uphold same.

20. In combination with pressure applying elements, a device as characterized, comprising a base, work supporting member erected thereon and adapted to yield upon the premature application of pressure thereto, an element associated with said base and adapted to be engaged with said member to prevent its yielding, said element adapted to be actuated by pressure exerting means upon its approximation to said member.

21. In combination with pressure apply- 130

- ing elements, a form adapted to support work to be subjected to pressure, and comprising a base on which a supporting member is yieldingly upheld, the construction and arrangement being such that if an extraneous object is interposed between the form and an approaching pressure element said supporting member will yield and the object will not be subjected to destructive pressure, and a locking element associated with the base and adapted to be actuated by said pressure element upon its approximation to the form to prevent the supporting member from yielding.
- 15 22. In a form as characterized, a base, walls supported thereon and adapted to normally yield under pressure and a member positioned on said base and movable into engagement with said walls to prevent depression thereof.
- 20 23. In a form as characterized, a base, walls yieldingly supported thereon, means adapted to prevent yielding of said walls, and actuating means operatively connected with said preventive means and extending a spaced distance above the walls.
- 25 24. In a form as characterized, a base, posts erected on said base, walls yieldingly supported between said posts, locking elements adapted to be engaged with said walls to prevent movement thereof and actuating means operatively connected with said locking elements and adapted to be actuated by an approximating pressure.
- 30 25. In combination with pressure applying elements, a form as characterized, comprising a base, walls erected thereon, perpendicularly thereto and adapted to turn on a horizontal axis when subjected to premature pressure, and means adapted to prevent said turning movement, said means adapted to be actuated by a pressure applying element upon its approximation to the form.
- 35 26. In combination with pressure applying elements, a form as characterized, comprising a base, spaced parallel walls erected thereon and adapted to turn upon a longitudinal axis when subjected to premature pressure, and means operable by a proximating pressure element to prevent said turning.
- 40 27. In a form as characterized, a base, spaced parallel walls, horizontally disposed pivots on which said walls are mounted and are adapted to turn under prematurely applied pressure, and means operable at a predetermined time to prevent said turning.
- 45 28. In a form as characterized, a base, adjustably spaced parallel walls, horizontally disposed pivots on which said walls are mounted and are adapted to turn under prematurely applied pressure, and means operable at a predetermined time to prevent said turning.

29. In a form as characterized, a base, adjustably spaced parallel walls, horizontally disposed resiliently supported pivots on which said walls are mounted and are adapted to turn under prematurely applied pressure and means operable at a predetermined time to prevent said turning.

30. In a form as characterized, spaced side walls and an end wall, said walls being so constructed and arranged that a side wall may be depressed without influencing either of the other walls, but that depression of the end wall will carry with it the contiguous ends of the side walls.

31. In a form as characterized, adjustably spaced side walls, and an end wall, said walls being so arranged and constructed that a side wall may be depressed without influencing either of the other walls, but that depression of the end wall will carry with it the contiguous ends of the side walls.

32. In a form as characterized, adjustably spaced side walls, and an end wall, said walls being resiliently supported, and so constructed and arranged that a side wall may be depressed without influencing either of the other walls, but that depression of the end wall will carry with it the contiguous ends of the side walls.

33. A form as characterized, comprising adjustably spaced resiliently supported side walls, and an end wall, said end wall comprising two sections each of which is resiliently supported, the construction and arrangement being such that either section may be depressed independent of the other and that when depressed it will carry with it the contiguous end of the respective side, and that either side may be depressed independent of its respective end section.

34. A form as characterized, comprising adjustably spaced side walls carried on resiliently supported pivots and a resiliently supported end wall, the arrangement and construction being such that a side wall may be depressed, or turned on its pivot, or both, independent of the end wall, but that depression of the end wall will cause depression of the adjoining ends of the side walls.

35. A form as characterized, comprising adjustably spaced side walls carried on resiliently supported pivots, and an end wall comprising two sections each of which is resiliently supported, the construction and arrangement being such that a side wall may be depressed or turned on its pivot, or both, independent of the end wall, but that depression of either section of the end wall will cause depression of the adjoining end of the respective side wall.

36. In a form as characterized, spaced side walls and an end wall said walls being so constructed and arranged that a side wall may be depressed without influencing either of the other walls, but that depression of the

end wall will carry with it the contiguous ends of the side walls, and means operatable at a predetermined time to prevent depression of said walls.

5 37. In a form as characterized, adjustably spaced side walls, and an end wall, said walls being so constructed and arranged that a side wall may be depressed without influencing either of the other walls, but that depression of the end wall will carry with it the contiguous ends of the side walls, and means operatable at a predetermined time to prevent depression of said walls.

10 38. In a form as characterized, adjustable spaced side walls, and an end wall, said wall being resiliently supported and so constructed and arranged that a side wall may be depressed without influencing either of the other walls, but that depression of the end wall will carry with it the contiguous ends of the side walls, and means operatable at a predetermined time to prevent depression of said walls.

15 39. A form as characterized, comprising adjustably spaced resiliently supported side walls, an end wall comprising two sections each of which is resiliently supported, the construction and arrangement being such that either section may be depressed independent of the other and that it will carry with it the contiguous end of the respective side and that either side may be depressed independent of its respective end section, and means operatable at a predetermined time to prevent depression of said walls.

20 40. A form as characterized, comprising adjustably spaced side walls carried on resiliently supported pivots, a resiliently supported end wall, the construction and arrangement being such that a side wall may be depressed, or turned on its pivot, or both, independent of the end wall, but that depression of the end wall will cause depression of the adjoining ends of the side walls, and means operatable at a predetermined time to prevent depression of the side walls.

25 41. A form as characterized comprising adjustably spaced side walls carried on resiliently supported pivots, an end wall comprising two sections, each of which is resiliently supported, the construction and arrangement being such that a side wall may be depressed, or turned on its pivot, or both, independent of the end wall, but that depression of either section of the end wall will cause depression of the adjoining end of the respective side wall, and means operatable at a predetermined time to prevent depression of said side wall.

30 42. In a form as characterized, a base, a frame slidably disposed thereon and adapted to be adjusted laterally thereon to and from the center thereof, a work supporting member carried by said frame, said member being adapted to yield under prematurely

applied pressure, and means adapted to be actuated by an approximating pressure element to prevent the members yielding.

43. In a form as characterized, a base, a frame slidably disposed thereon and adapted to be adjusted laterally to and from the center thereof, posts erected on said frame, a wall positioned between said posts and movable vertically relative thereto, the lower edge of said wall being a spaced distance above said base, resilient means opposing the downward movement of the wall, a locking element disposed on the base and adapted to be projected under the wall to prevent downward movement thereof, actuating means operatively connected with said locking element and operating means connected with said actuating means and extending a spaced distance above the posts.

44. In a form as characterized, a base, a frame slidably disposed thereon and adapted to be adjusted laterally to and from the center thereof, posts erected on said frame, a side wall pivotally mounted between said posts and adapted for vertical and rotary movement relative thereto, said wall terminating a spaced distance above the base, resilient means opposing the downward movement thereof, a locking element disposed on the base and adapted to be projected under the wall to prevent downward movement thereof, actuating means operatively connected with said locking element and operating means connected with said actuating means and extended a spaced distance above the post.

45. In a form as characterized, a base, a frame slidably disposed thereon and adapted to be adjusted laterally to and from the center thereof, posts erected on said frame, having vertical slots in their opposed sides, blocks slidably disposed in said slots, springs adapted to hold said blocks at the upper end of the slots, a wall pivotally mounted in the blocks, a locking element disposed on the base and adapted to be projected under the wall to prevent downward movement thereof, actuating means operatively connected with said locking elements and operating means connected with said actuating means and extending a spaced distance above the posts.

46. In a form as characterized, a base, a frame slidably disposed thereon and adapted to be adjusted laterally to and from the center thereof, posts erected on said frame, having vertical slots in their opposed sides, blocks slidably disposed in said slots, springs adapted to hold said blocks at the upper end of said slots, a side wall pivotally mounted in the blocks, an end wall slidably associated with the front post, resilient means adapted to hold said end wall at its upper limit of movement, interengageable means between the end wall and the adja-

cent end of the side wall whereby depression of the end wall will cause a corresponding depression of the side wall, locking elements disposed on the base and adapted to be projected under the walls to prevent downward movement thereof, actuating means operatively connected with said locking elements and operating means connected with said actuating means and extending 10 a spaced distance above the posts.

47. In a form as characterized, a base, a frame slidably disposed thereon and adapted to be adjusted laterally to and from the center thereof, posts erected on said frame 15 having vertical slots in their opposed sides, blocks slidably disposed in said slots, springs adapted to hold said blocks at the upper end of the slots, a side wall pivotally mounted in the blocks, an end wall slidably associated with the front post, resilient 20 means adapted to hold said end wall at its upper limit of movement, interengageable means between the end wall and the adjacent end of the side wall which prevents rotary movement of the side wall and without 25 first depressing it slightly to free it from engagement with the end wall but whereby primary depression of the end will carry the side wall with it.

48. In a form as characterized, a base, a frame slidably disposed thereon and adapted to be adjusted laterally to and from the center thereof, posts erected on said frame, a wall positioned between said posts and 30 movable vertically relative thereto, the lower edge of said wall being a spaced distance above the base, resilient means adapted to hold the wall at the upper limit of its movement, a bar slidably positioned longitudinally on the base, a rod slidably mounted on the rear post and extended a spaced distance thereabove, operative connections between said rod and said bar whereby depression of the rod will move the bar, resilient means adapted to return the bar and rod to normal position, locking elements 35 adapted to be engaged with the walls to prevent depression thereof, and operative connections between said elements and the sliding bar.

49. In a form as characterized, a base, a pair of frames slidably disposed thereon and adapted to be adjusted laterally to and from the center thereof, posts erected on the rear 45 corners of said frames, other posts of less height erected on the front corners, the front and rear posts on the respective sides having vertical slots in their opposed sides, spring supported blocks slidably mounted in 50 said slots, said side walls pivotally mounted in said blocks, the front posts having vertical grooves, in their opposed sides, an end wall slidably mounted in said grooves, resilient means adapted normally to hold said 55 end wall at the upper limit of its movement,

interengaging means between the end and side walls whereby a side wall may be depressed independent of the end wall, but depression of the end wall will carry the side wall with it and means adapted to lock the 70 walls in their elevated position.

50. A form as characterized, a base, a pair of frames slidably disposed thereon and adapted to be adjusted laterally to and from the center thereof, work support- 75 ing members carried by each of said frames, said members being adapted to yield under prematurely applied pressure, and means adapted to be actuated by an approximating pressure element to prevent the members 80 yielding.

51. In a form as characterized, a base, a pair of frames slidably disposed thereon and adapted to be adjusted laterally to and from the center thereof, posts erected on said 85 frames, side walls pivotally mounted between said posts and adapted for vertical and rotary movement relative thereto, said walls terminating a spaced distance above the base, resilient means opposing downward 90 movement thereof, locking elements disposed on the base and adapted to be projected under the walls to prevent downward movement thereof, actuating means operatively connected with said locking elements 95 and operating means connected with said actuating means and extended a spaced distance above the posts.

52. In a form as characterized, a base, a pair of frames slidably disposed thereupon 100 and adapted to be adjusted laterally to and from the center thereof, posts erected on the corners of said frames, the front and rear posts respectively having vertical slots in their opposed sides, blocks slidably disposed 105 in said slots, springs adapted to hold said blocks at the upper end of the slots, side walls pivotally mounted in the blocks, locking elements disposed on the base and adapted to be projected under the walls to 110 prevent downward movement thereof, actuating means operatively connected with said locking elements and operating means connected with said actuating means and extending a spaced distance above the posts. 115

53. In a form as characterized, a base, a pair of frames slidably disposed thereupon and adapted to be adjusted laterally to and from the center thereof, posts erected on the corners of said frames, the front and rear 120 posts respectively having vertical slots in their opposed sides, blocks slidably disposed in said slot, springs adapted to hold said blocks at the upper end of said slots, side walls pivotally mounted in the blocks, an 125 end wall slidably associated with the front posts, resilient means adapted to hold said end wall at its upper limit of movement, interengaging means between the end wall and the adjacent ends of the side walls whereby 130

- depression of the end wall will cause a corresponding depression of the side walls, locking elements disposed on the base and adapted to be projected under the walls to 5 prevent downward movement thereof, actuating means operatively connected with said locking elements and operating means connected with said actuating means and extending a spaced distance above the posts.
- 10 54. In a form as characterized, a base, a pair of frames slidably disposed thereupon, and adapted to be adjusted laterally to and from the center thereof, posts erected on the corners of said frames, the front and rear 15 posts respectively having vertical slots in their opposed sides, blocks slidably disposed in said slots, springs adapted to hold said blocks at the upper end of said slots, side walls pivotally mounted in the blocks, an 20 end wall slidably associated with the front posts, resilient means adapted to hold said end wall at its upper limit of movement, and interengagable means between the end walls and the adjacent ends of the side walls 25 which prevent rotary movement of a side wall and without first depressing it slightly to free it from engagement with the end wall but whereby primary depression of the end will carry the side walls with it.
- 30 55. In a form as characterized, a base, a pair of frames slidably disposed thereon and
- adapted to be adjusted laterally to and from the center thereof, posts erected on said frames, walls positioned between said posts and movable vertically relative thereto, the 35 lower edge of said walls being spaced a distance above the base, resilient means adapted to hold the walls at the upper limit of movement, a bar slidably positioned longitudinally on the base, a rod slidably mounted on 40 the rear post and extended a spaced distance thereabove, operative connections between said rod and said bar whereby depression of the rod will move the bar, resilient means adapted to return the bar and rod to normal 45 position, locking elements adapted to be engaged with the walls to prevent depression thereof, and operative connections between said elements and the sliding bar.
56. In a form as characterized, a base, 50 side and end walls suitably supported thereon, said walls adapted normally to yield vertically under moderate pressure, means for applying pressure vertically to said walls, and means to prevent depression of the walls 55 under pressure, the last named means adapted to be actuated by the first named means upon its close approximation to the top of the walls.
